UNITED STATES PATENT OFFICE

JAMES L. ADAMS, JR., OF EAST CHICAGO, INDIANA, ASSIGNOR OF NINE-TENTHS TO GRAVER CORPORATION, OF EAST CHICAGO, INDIANA, A CORPORATION OF ILLINOIS

METAL-SPINNING MACHINE

Application filed February 23, 1928. Serial No. 256,324.

This invention relates to an apparatus for spinning metallic discs adapted for use as the heads of tank structures. In the spinning process a flat metallic disc of circular shape is rotated and at the same time bent to give it an arcuate shape.

In the accompanying drawings which illustrate the present preferred embodiment of my invention,

10. Figure 1 is a plan view, parts being shown in section,

Figure 2 is an end elevation,

Figure 3 is a longitudinal vertical section on the line III—III of Figure 1,

15. Figure 4 is a side elevation, and

Figure 5 is a section on the line V—V of Figure 4, parts being removed for clearness.

The preferred form of apparatus illustrated in the drawings comprises a stationary frame or guide on which the motors for actuating the machine and the cooperating elements are mounted. The stationary frame or guide cooperates with a sliding frame to which is secured a rack. The stationary 20 guide, the sliding frame, and the rack are curved. The sliding frame forms a part of a yoke on another part of which is a clamp for clamping the disc to be spun.

A spinning wheel is arranged to contact 30 with the outside of the disc and a backing roll is provided to contact with the inner surface of the disc. Both the spinning wheel and the backing roll are revolved so as to spin the disc.

35. In spinning the disc and making it dish shaped, the spinning and backing rolls are revolved in order to spin the disc, and the sliding frame is moved relative to the spinning and backing rolls through the rack carried by the sliding frame, and a pinion actuated by a motor.

40. Referring more particularly to the drawings, the apparatus comprises a base 2, on which is mounted a stationary frame or guide 3. The guide has a vertical extending web 4, at the top and bottom of which are horizontally extending base portions 5 and 6 respectively. At the outer edges of the base 45 portions 5 and 6 are vertical flanges 5' and

6', respectively. The flanges are arcuate and form a guide for a sliding frame 8.

The apparatus is made double-sided so that two discs can be operated upon at substantially the same time. The actual spinning of the two discs may not be done at the same time, but while one disc is being spun the other disc may be connected to the opposite side of the machine so that it is ready for spinning when the first disc is finished. 55 The two sides of the machine are identical so that it will be necessary to describe only one side.

The sliding frame 8 is yoke shaped, as clearly shown in Figure 5. To the inner leg 65 10 of the yoke is secured a rack 11, which is actuated through a pinion 12, worm wheel 13, and worm 14 from a motor 15. The outer end of the yoke forms a bearing 17 for a clamp screw 18, which actuates a clamp 19 for 70 securing the disc 20 to the yoke.

The clamp 19 is illustrated in detail in Fig. 1 and comprises the clamping screw 18 which may be rotated by turning the handle 21. The disc 20 is clamped between a cup-shaped clamping member 22 and a pin 23 rotatable in a bearing 24 which forms a portion of the yoke 8. A ball-bearing 25 is provided for the clamp so that the cup-shaped member 22 and the pin 23 may rotate 75 with the disc while the rest of the clamp remains stationary.

The disc 20 is rotated by means of a spinning roll 30, which contacts with the outer surface of the disc, and a backing roll 31, 85 which contacts with the inner surface of the disc. Both of these rolls are actuated from a spinning motor 32. The backing roll 31 is secured to a shaft 33 mounted in a bearing 34. The shaft 33 is rotated through a worm wheel 35 which is rotated by a worm 36 on the motor shaft 37.

The spinning roll 30 is secured to a shaft 40, supported by a bracket 41, and is rotated through a gear 42 which meshes with a gear 43 secured to the shaft 33. Rotation of the motor 32 causes rotation of the spinning roll 30 and the backing roll 31, thereby rotating the disc 20.

The shaft 40 of the spinning roll 30 is 100

supported in a sleeve 50 which in turn is supported by the bracket 41. The sleeve 50 is bored eccentrically so that when it is rotated in its bearings it causes the spinning roll 30 to move toward or away from the disc 20. The eccentric sleeve 50 is provided with a worm wheel 51, which is rotated through a worm 52 and handle 53. Rotation of the handle 53 causes the spinning roll 30 to be moved toward or away from the disc 20. The shaft 40 and the spinning wheel 30 may also be moved longitudinally by rotation of the handle 54 which turns worm 55, worm wheel 60, and pinion 61 secured to shaft 62. The pinion 61 meshes with a rack 63 formed on the sleeve 50. These adjustments of the spinning roll 30 longitudinally of the shaft 40 and toward and away from the disc 20 enable discs to be spun to different curvatures.

The sliding frame 8 carrying the rack 11 is caused to move relative to the spinning roll 30 and backing roll 31 by the motor 15. The motor shaft 16 has a worm 14 secured thereto which meshes with a worm wheel 13 (see Figs. 3 and 4). The worm wheel 13 is secured to a shaft 71 which carries a pinion 12 at its upper end. The pinion 12 meshes with the rack 11 secured to the lower left-hand flange 75, as viewed in Fig. 2, of the sliding frame 8. The upper left-hand flange 74 of the sliding frame 8 is guided by the upper left-hand flange 5' of the stationary frame 3, and the lower left-hand flange 75 of the sliding frame 8 is guided by the lower left-hand flange 6' of the stationary frame 3, as viewed in Fig. 2. When the motor 15 is running it causes the sliding frame 8 to be moved relatively to the spinning roll 30 and the backing roll 31. The rack 11 which is secured to the arm 10 of the sliding yoke shaped frame 8 causes the whole frame 8 and the clamp 19 for the disc 20 to be moved with respect to the spinning and backing rolls. The position of the clamp 19 and handle 21 for actuating the clamp are shown in chain lines in Fig. 1 in the position which they assume after the rack 11 and frame 8 have been moved due to the movement of the rack 11 by its driving pinion 12. It will be understood that when the motor 15 is rotated it moves the whole yoke shaped frame 8 from the dotted line position 76 to the chain line position 77, shown in Fig. 1. Movement of the frame 8 and the clamp 19 moves the disc 20 to the left of spinning roll 30 and backing roll 31, as viewed in Fig. 1. This movement of the disc to the left, in conjunction with the spinning of the disc through the rolls 30 and 31 causes the disc to be dished.

In the operation of forming the disc 20 to an arcuate shape, the disc is secured in position by the clamp 19 by turning the handle 21. The motor 32 is then started which rotates spinning roll 30 through shaft 40,

gears 42, 43, shaft 33, worm wheel 35, and worm 36. The backing roll 31 is rotated through shaft 33, worm wheel 35 and worm 36. Rotation of the spinning and backing rolls causes rotation of the disc 20. The motor 15 is then started, and through the worm 14, worm wheel 13 and pinion 12 causes the rack 11 and the sliding frame 8 by which the rack is carried, to move to the left, as viewed in Fig. 1.

This forms the disc 20 into an arcuate shape suitable for use as a head of a container.

As previously stated, the apparatus is preferably made double sided so that two discs may be arranged in the machine at the same time. The opposite sides of the machine are similar in construction. I have already described the parts shown in the upper half of Fig. 1. The corresponding parts, shown in the lower half of Fig. 1, are designated with the same reference numerals with an "a" suffixed thereto. The rack 11^a is actuated from a motor 15^a through worm 14^a, worm wheel 13^a and pinion 12^a. Rotation of the pinion 12^a moves the rack 11^a to the left, as viewed in Fig. 1. In a manner similar to that already described, movement of the rack 11^a to the left causes the sliding frame 8^a, the clamp 19^a, and the disc 20^a to move to the left relative to the spinning roll 30^a and the backing roll 31. The double-sided machine hereinabove described enables the disc 20^a to be clamped to the sliding frame 8 while the disc 20 is being spun.

I have illustrated and described the present preferred embodiment of my invention. It is to be understood, however, that the invention may be otherwise embodied within the scope of the following claims.

I claim:

1. A machine for spinning dished articles from a metal sheet, comprising two rolls of substantial disc shape adapted to contact at their edges with opposite surfaces of the sheet, a mounting for the sheet for positioning it between the rolls, means for rotating the rolls to spin the sheet, and means for moving the sheet mounting in a curved path relative to the rolls.

2. A machine for spinning dished articles from a metal sheet, comprising two rolls of substantial disc shape adapted to contact at their edges with opposite surfaces of the sheet, a mounting for the sheet for positioning it between the rolls, means for rotating the rolls to spin the sheet, and means for moving the sheet mounting in a curved path toward and away from the rolls in order to dish the sheet.

3. A machine for spinning dished articles from a metal sheet, comprising deforming means for the sheet adapted to contact with opposite sides thereof and to spin it when they are rotated, a curved slicing frame to which the sheet can be secured, a stationary

guide frame cooperating with the sliding frame and having the same curvature, and means for moving the sliding frame along the guide frame relative to the deforming means to give the sheet a dished shape.

5 4. A machine for spinning dished articles from a metal sheet, comprising deforming means for the sheet adapted to contact with opposite sides thereof and to spin it when they are rotated, a curved sliding frame to which the sheet can be secured, a stationary guide frame cooperating with the sliding frame and having the same curvature, and a rack on one of the frames cooperating with 10 a driving pinion carried by the other frame for moving the sliding frame along the guide frame relative to the deforming means to give the sheet a dished shape.

15 5. A machine for spinning dished articles from a metal sheet, comprising deforming means for the sheet adapted to contact with opposite sides thereof and to spin it when they are rotated, a curved sliding frame to which the sheet can be secured, a stationary guide frame cooperating with the sliding frame and having the same curvature, and a rack on the sliding frame cooperating with 20 a driving pinion carried by the stationary frame for moving the sliding frame along the guide frame relative to the deforming means to give the sheet a dished shape.

25 6. A machine for spinning dished articles from a metal sheet, comprising a curved sliding frame to which the sheet can be secured, a stationary guide frame cooperating with the sliding frame, a spinning roll and a backing roll adapted to contact with opposite surfaces of the sheet, means to rotate said rolls to spin the sheet, and means for moving 30 the sliding frame along the guide frame relative to said rolls in order to give the sheet a dished shape.

35 7. A machine for spinning dished articles from a metal sheet, comprising a curved sliding frame to which the sheet can be secured, a stationary guide frame cooperating with the sliding frame, a spinning roll and a backing roll adapted to contact with opposite surfaces of the sheet, means to rotate 40 said rolls to spin the sheet, means for moving the sliding frame along the guide frame relative to said rolls in order to give the sheet a dished shape, and means to vary the pressure of the spinning roll on the sheet.

45 8. A machine for spinning dished articles from a metal sheet, comprising a curved sliding frame to which the sheet can be secured, a stationary guide frame cooperating with the sliding frame, a spinning roll and a backing roll adapted to contact with opposite surfaces of the sheet, means to rotate 50 said rolls to spin the sheet, means for moving the sliding frame along the guide frame relative to said rolls in order to give the sheet a dished shape, the spinning roll having its drive

55 shaft mounted in an eccentrically bored sleeve mounted in bearings, and means for rotating the sleeve to vary the pressure of the spinning roll on the sheet.

60 9. A machine for spinning dished articles from a metal sheet, comprising a curved sliding frame to which the sheet can be secured, a stationary guide frame cooperating with the sliding frame, a spinning roll and a backing roll adapted to contact with opposite surfaces of the sheet, means to rotate 65 said rolls to spin the sheet, means for moving the sliding frame along the guide frame relative to said rolls in order to give the sheet a dished shape, the spinning roll having its drive shaft mounted in an eccentrically bored sleeve mounted in bearings, a worm wheel on the sleeve, and a worm 70 cooperating therewith, whereby the eccentric sleeve may be rotated to vary the pressure of the spinning roll on the sheet.

75 10. A machine for spinning dished articles from a metal sheet, comprising a curved sliding frame to which the sheet can be secured, a stationary guide frame cooperating with the sliding frame, a spinning roll and a backing roll adapted to contact with opposite surfaces of the sheet, means to rotate 80 said rolls to spin the sheet, means for moving the sliding frame along the guide frame relative to said rolls in order to give the sheet a dished shape, means to vary the pressure of the spinning roll on the sheet, and means for adjusting the spinning roll longitudinally 85 of its axis of rotation.

90 In witness whereof, I hereunto subscribe my name.
